UNITED STATES PATENT OFFICE.

FRANK D. SHEPHERD, OF SALT LAKE CITY, UTAH.

VALVE AND HEAD FOR INTERNAL-COMBUSTION ENGINES.

1,262,396.

Specification of Letters Patent.

Patented Apr. 9, 1918.

Application filed December 22, 1916. Serial No. 138,453.

To all whom it may concern:

Be it known that I, FRANK D. SHEPHERD, a citizen of the United States, and resident of Salt Lake City, in the county of Salt Lake, and in the State of Utah, have invented a certain new and useful Improvement in Valves and Heads for Internal-Combustion Engines, and do hereby declare that the following is a full, clear, and exact 10 description thereof.

The object of my invention is to improve the construction of internal combustion engines with especial reference to the valve mechanism and the cylinder head to the end 15 that the valve will be easy of manufacture, readily accessible and capable of efficiently performing its function, and the cylinder head may be convenient of manufacture and application to the cylinder and peculiarly 20 well suited for the valve mechanism, and with the object stated in view my invention consists in the construction substantially as hereinafter specified and claimed.

In the accompanying drawings—
25 Figure 1 is a vertical section through an internal combustion engine having one form of my valve;

Fig. 2 is a similar view but showing only the valve mechanism, and immediately adjacent parts, illustrating a different form of 30 my invention;

Fig. 3 is a like view to Fig. 2, showing still another form of my invention.

Giving a detailed description of the construction shown in the drawings, there is 35 a water jacketed engine cylinder 10. The cylinder head 11 is made separate from the cylinder and secured thereto by bolts 12, the abutting faces of cylinder and head being 40 plane and a gas tight joint secured by a gasket between them. Leading from the dome-shaped cavity, or depression in the inner side of the head is a port, or passage 13 at the outer end of which is located the valve 45 mechanism for controlling the flow through the port. It will be seen that the port is formed wholly in the head and its one open side is closed by the adjacent end of the cylinder when the head is bolted to the latter. 50 The valve seat 14 is a bevel surface formed on the cylinder end adjacent said port at one extremity of the chamber, or passage 15 through which the gas supply, or the exhaust passes to and from the cylinder by 55 way of said port 13. In alignment with the passage 15, and thus parallel with the length-

tudinal axis of the cylinder and extending from the port 13 outward through the cylinder head is a cylindrical chamber 16. The valve has a beveled seat-engaging face 17 and a head, or body 18 which reaches therefrom across the port 13 and has an extension 19 which enters said chamber 16, and having a sliding fit within the latter said chamber 16 constitutes a lateral support for the 60 valve and a guide in which it reciprocates. Preferably the valve extension 19 is chambered, or provided with a cavity 20 in its outer end to receive one end portion of a helical spring 21 situated in the chamber 16 65 whose other end has a thrust bearing, or support upon the outer end wall, or head 22 of the chamber 16. Said spring 21 serves yieldingly to hold the valve to its seat and to return it to its seat when it has been 70 lifted, as by the usual cam device shown in the drawings, but not necessary to be described in detail since my invention has nothing to do with the construction of the particular device for lifting the valve from 75 its seat. The casing head 22 may, as illustrated in Fig. 1, be a simple cover plate bolted to and detachable or removable from the side walls which inclose the chamber 16, in which case said side walls are integral 80 with the cylinder head; or as shown in Fig. 2, the bonnet formation in which the head is integral with the side walls may be employed, in which case the head and side walls are together removable intact from 85 the cylinder head. But whatever construction may be employed in this regard, it has the important characteristic of non-communication with the external atmosphere, so that even though there might be leakage of 90 gas into the valve spring-supporting and guiding chamber 16, there can be no escape of the gas from said chamber 16, and, hence, loss of power and waste from leakage is 95 avoided. In order to assure gas tight joints, a gasket is applied between the meeting 100 faces of the parts. The side walls of the chamber 16 are constructed for rapid cooling, as by being water jacketed, or provided with ribs, or fins to constitute radiating 105 surfaces of large area.

The valve seating spring requires to be safeguarded against the injurious effects of the high temperatures in the adjacent passages. As the valve head, or body is a thick 110 substantial mass reaching, even when the valve is in a closed position, across the port

13, to the inner end of the guiding chamber 16, the spring is thus situated advantageously for its protection against loss of temper by reason of high temperatures. 5 Still further to protect the spring and the thin walls of the valve extension 19, I place a body of heat-resisting material 23, such as a disk of asbestos, between the inner end of the spring and the port 13, which disk is 10 conveniently placed at the bottom of the cavity 20 of the extension 19.

To reduce, or diminish as far as possible unoccupied space within the chamber 16, I place within the coils of the spring a filling 15 device which may be attached either to the valve, or to the casing, or in part to each, said filling device occupying as much space in the direction of movement of the valve, as is possible without stopping, or restricting 20 the play, or movement of the valve necessary for the performance of its function in moving from its seat to open the port 13. As shown in Fig. 1, said filling device is in the form of a solid cylindrical plug 25 having at one end a disk form head 26 which bears against the heat resisting disk 23 and it is engaged by the inner end of the coil spring. If desired, the headed filling plug can be placed in the reversed position from 30 that shown in Fig. 1. As shown in Figs. 2 and 3 the filling plug may be integral with the valve. The filling plug instead of being a solid cylindrical body may be a shell, or tube with one end closed and at its other 35 end threaded, or otherwise secured in a hole provided in the valve head, or body.

By the employment of said filling device, the unoccupied space within the valve and its casing is reduced to a minimum, and 40 hence, should there be any leaking of gas by reason of a worn condition of that part of the valve which plays in and is guided by the interior of the casing, the quantity finding its way into the valve and its casing 45 would be so small as to be negligible.

If desired, one or more annular grooves 50 may be provided in the periphery of the guide-forming extension of the valve for a lubricant, although practice has shown that lubrication is not indispensable. It is 55 not necessary to provide any special lubricant supply when it is desired to use a lubricant, because oil for the piston head of the engine will find its way to the valve. No adjusting means for the spring is necessary 60 with my device because the spring can, when originally applied, be given just the right tension. However, should it be desired to change the tension of the spring 65 that could be done by the employment of disks or washers at either end of the spring whose tension could be increased by the presence of one or more washers and its tension decreased by the removal of one or 70 more of them.

As shown in Fig. 1, in order to maintain the spring in a central position, I place over its upper end a flanged disk or cup 210 which closely fits the chamber 16. Thus sidewise play of the spring is prevented 70 which is important as in the construction shown in Fig. 1, to prevent contact of the upper edge of the valve extension with the coils of the spring.

The valve head, or body may be cylindrical, but I prefer to give it the hollowed out, or concave form shown in the drawing so as to provide ample space about the valve head for the passage of the gas.

The construction shown in Fig. 3 is the 80 same as that shown in Fig. 2, excepting that the casing head 22 is detachable as in Fig. 1, and the side walls of said casing are integral with the cylinder head and are provided with the well-known ribs or fins for 85 radiating heat for cooling purposes.

It will be seen that access to the valve mechanism may easily and quickly be had simply by removing the head of the chamber 16 when the head alone is removable, or by removing the entire bonnet when that form of construction is used, and it will also be evident that complete and ready access to cylinder and the valve mechanism may be had by lifting the cylinder head 90 with such parts of the valve mechanism as may be carried therewith. As the valve head and seat are no larger in diameter than the diameter of the chamber 16, the valve may be readily removed when the bonnet, or 95 the casing head 22 is removed.

As will be evident, especially since the closing of the valve is effected by the expansive action of the spring, the closing of the valve is produced very positively, and 105 the construction is simple by reason of the fewness of the parts, and it is strong since the parts are stout and compact. With the location that I give it, space that is otherwise not utilized in L-head and T-head engines, is utilized, there is an increase of power obtained from the engine, and the parts are most readily accessible for removal for cleaning, or valve grinding. For the application of the grinding tools suitable provision is made, such as a slot, or 110 notch 28 in the valve head.

In constructing an engine embodying my invention, although the spark plug 29 may be applied in any suitable place, I prefer 115 to place it in the center of the head of the cylinder, as shown in Fig. 1.

I show in the drawings but a single valve for the engine, but it, of course, will be understood there are two valves, one for 120 the intake and the other for the exhaust. Although the engine shown is a water jacketed one, it is to be understood my valve mechanism is applicable to air cooled as well as water cooled engines, and its employ- 125 130

ment, of course, does not depend upon the number of engine cylinders for it is applicable to one cylinder, or any number of cylinders, and when more than one cylinder is used, whether they are cast separately, or *en bloc*.

It will be evident from the various forms in which I illustrate my invention as embodied, that such invention is not limited to any precise construction and relative arrangement of the parts, and hence, it is to be understood that I do not restrict myself even to such particular constructions and relative arrangements of the parts as are shown in the drawings.

Having thus described my invention what I claim is—

1. The combination of an engine cylinder having a valve-controlled passage with a valve seat, a puppet valve having a guide-forming extension, a guide connected with the cylinder in a part surrounding said extension, a coil spring bearing at one end against an internal surface on said extension, and at its other end against a relatively stationary part, and a body of heat-resisting material interposed between the spring and a part of the valve adjacent said valve controlled passage.

2. The combination of an engine cylinder having a valve-controlled passage with a valve seat, a puppet valve having a guide-forming extension, a guide connected with the cylinder in a part surrounding said extension, said extension being hollow to receive a spring, a coil spring bearing at one end against an internal surface on said extension, and at its other end against a relatively stationary part, and a body of heat-resisting material situated in the bottom of the hollow part of said extension.

3. The combination of an engine cylinder having a valve-controlled passage with a single stationary valve seat, a puppet valve having a guide-forming extension, and having a surface to coöperate with said single stationary seat, a guide connected with the cylinder in a part surrounding said extension and closed on all sides to the external atmosphere, said extension being hollow to receive a spring, a coil spring bearing at one end against an internal surface on said extension, and on its other end against a relatively stationary part, and a body of heat-resisting material situated in the bottom of the hollow part of the extension.

4. The combination of an engine cylinder having a valve-controlled passage with a valve seat, a puppet valve having a guide-forming extension, a guide connected with

the cylinder in a part surrounding said extension, and a coil spring bearing at one end against an internal surface on said extension, and at its other end against a relatively stationary part that extends over the sides of the spring adjacent its end so as to confine the spring against lateral movement, said relatively stationary part being a disk with a flange that fits said guide.

5. The combination of an engine cylinder having a valve-controlled passage with a valve seat, a puppet valve having a guide-forming extension, a guide connected with the cylinder in a part surrounding said extension, a coil spring bearing at one end against an internal surface on said extension, and at its other end against a relatively stationary part, a filling member extending partially through the spring on the inside thereof, its length being substantially less than the distance between the bearings for the spring ends when the valve is on its seat, and a body of heat-resisting material interposed between the spring and a part of the valve adjacent said valve controlled passage.

6. The combination of an engine cylinder, a cylinder head removably secured to the cylinder, said head having a valve-controlled port formed within the head with an open side toward the cylinder end and closed thereby when the head is on the cylinder, a valve for controlling said port having a guide-forming extension, the valve seat being formed on the cylinder end and being uncovered when the head is removed, a guide chamber receiving said extension carried by and removable with the head, said guide chamber being closed to the external air and having a removable cap at its outer end, and a spring within said chamber having a bearing at one end upon said removable cap and at its other end bearing upon the valve extension within the chamber.

7. The combination of an engine cylinder having a valve-controlled passage with a valve seat, a puppet valve having a hollow guide-forming extension, a guide connected with the cylinder in a part surrounding said extension, a coil spring extending into the hollow extension and bearing at one end against an internal surface on said extension, and at its other end against a relatively stationary part that extends over the sides of the spring adjacent its end so as to confine the spring against lateral movement.

In testimony that I claim the foregoing I have hereunto set my hand.

FRANK D. SHEPHERD.
